UNITED STATES PATENT OFFICE.

ARTHUR LEFEVRE, JR., OF HOUSTON, TEXAS, ASSIGNOR, BY MESNE ASSIGNMENTS, TO THE TEXAS COMPANY, OF NEW YORK, N. Y., A CORPORATION OF DELAWARE.

DISPLAY DEVICE.

Application filed December 3, 1926. Serial No. 152,383.

This invention relates to a novel advertising display device and more particularly to a device for displaying a thin film of viscous liquid, such for example, as motor or lubricating oil.

It is an object of the invention to provide a device for displaying viscous liquid such as motor or lubricating oil, in the form of a continuously flowing, broad and unbroken film, in order to visibly demonstrate the body and color of the liquid.

Another object of the invention is to provide an advertising display device, wherein the liquid being displayed is recirculated continuously, so that the display may be continued indefinitely with a given quantity of liquid.

Still another object of the invention is to provide converging guides between which a film of liquid is maintained.

A further object of the invention is to provide means for circulating the liquid through the device, and means for regulating the flow of liquid therethrough.

Other and incidental objects, advantages and features of the invention will readily appear, as the following description, taken in connection with the accompanying drawings, proceeds.

In the drawings, Figure 1 is a view in front elevation of an advertising display device embodying the features of my invention.

Figure 2 is a view in end elevation, partially in section, of the apparatus shown in Figure 1, and

Figure 3 is an enlarged sectional view of the oil supply pipe, showing the manner of connecting it with the by-pass pipe.

Referring to the drawings, there is indicated generally by the numeral 10, a cabinet adapted to support the display device, and to contain at least a portion of the operating mechanism. The cabinet consists of a table portion 11 and an upright portion 12, disposed at the rear of the table.

Concealed from view, within the cabinet and below the table 11, there is a reservoir or sump 13 adapted to contain the viscous fluid used in the demonstration. A cylindrical strainer 14 is positioned within the sump 13,

and into the strainer there extends an end of a suction pipe 15, the opposite end of which leads to the suction side of a pump 16, which is operated by a motor 17, the pump and motor being mounted upon a support 30 55 which rests upon halves of sponge rubber balls 31 to eliminate vibration noises. A supply pipe 18 connects at one end with the discharge or pressure side of the pump 16, and extends upwardly through the upright 60 portion of the cabinet for a considerable distance. The upper end of the supply pipe is bent to form an inverted U and depends into a substantially horizontally disposed receptacle or spout 19 which projects through the 65 front wall of the upright portion of the cabinet. Turn-buckles 20 secured at one end to the rear of the spout 19, and at the other end to the back of the cabinet, are provided so that the position of the spout 70 may be suitably adjusted as required.

A receiving receptacle or container 21, which is formed with a false bottom, is suitably mounted on the table 11, directly over an opening which is provided in the latter. 75 The receptacle is provided with a truncated, substantially conical lining 22, which extend downwardly and projects for a short distance into a somewhat similarly shaped splash guard 23, which in turn has its open 80 lower end disposed over the open upper end of the reservoir 13, so that any liquid discharge into the receptacle will gravitate to the reservoir, without any danger of splashing or the loss of any of the liquid.

The forward end of the spout 19 is formed with a horizontally disposed lip 24, to each of the opposite ends of which there is soldered or otherwise secured an end of a filament, preferably in the form of a brass 90 wire 25. The two wires depend from the lip, extending downwardly through the open end of the receptacle 21, and into the splash guard 23, where they are suitably drawn and fastened together. The extreme lower 95 ends of the wires are secured to a weight 26 which is thereby suspended within the splash guard so as to maintain the wires taut.

A by-pass pipe 27 having a valve 28 con- 100

nects at one end with the supply pipe 18, while its opposite end extends into the reservoir 13, so that a portion of the liquid pumped through the supply line may be returned to the reservoir before ever reaching the spout 19. A valve preferably in the form of a needle valve 29 is positioned in the supply line 18 for controlling the flow of liquid through the line. By a proper manipulation of the valves 28 and 29 the quantity of liquid finally delivered to the spout 19 may be easily controlled and regulated.

The connection between the by-pass line 27 and the supply pipe 18 is as shown in section in Figure 3. It will be seen that the by-pass pipe extends a short distance into the supply pipe and that it is formed with a beveled lip 32 on its upper side to insure the certain by-passing of the liquid when the valve 28 is opened.

It will be seen that a regulated supply of liquid is continuously pumped to the spout 19, the level of the liquid therein gradually rising until it begins to flow over the edge of the lip 24. As the viscous liquid passes over the lip it contacts with the two filaments or wires 25, the upper ends of which are spaced somewhat apart, and because of the viscosity of the liquid, it clings to the wires and forms a thin film between them, gradually flowing downward toward the point at which the wires converge. A baffle or bubble skimmer 33 is mounted between the opposite sides of the spout, with its lower edge at a sufficient height above the bottom of the spout to skim such air bubbles as may by chance be present in the liquid as it passes slowly beneath the baffle.

When the liquid has descended the entire length of the wires, it gravitates into the reservoir 13, from which it may again be drawn by the suction of the pump 16 to be again recycled through the system. Thus a given quantity of liquid may be used in maintaining a continuous flow through the apparatus. The thin film of liquid spread between the two suspended wires renders certain characteristics of the liquid visible to the eye, so that its color may be readily observed and its body demonstrated by the broad unbroken film maintained between the wires.

Apparatus of preferred form and construction has been illustrated and described for the purpose of showing a way in which this invention may be practiced, but the inventive thought upon which the invention is based is broader than this illustrative embodiment thereof and no limitations are intended other than those imposed by the appended claims.

What I claim is:

1. An advertising display device, comprising a pair of vertically disposed filamentary guides converging at their lower extremi-

ties, and means for continuously discharging liquid between the spaced upper ends of the guides.

2. An advertising display device comprising a horizontally disposed adjustable spout having a pouring lip at its forward end, a filamentary guide secured to each extremity of the lip and depending therefrom, means for securing the lower ends of the guides together, means at the lower ends of the guides for maintaining them constantly taut, and means for continuously supplying liquid to the spout from which it flows downwardly between the guides in the form of a sheet-like film.

3. An advertising display device, comprising a pair of vertically disposed converging guides spaced apart at their upper ends and joined together at their lower ends, means disposed at the lower ends of said guides for keeping them taut, and means for continuously discharging liquid between the spaced upper ends of the guides.

4. An advertising display device, comprising a cabinet formed with a table portion and an upright portion, a spout having a lip at its forward end extending through the front wall of the upright portion at a point above the table, a guide depending from each end of said lip and extending through an opening in the table, means for securing the lower ends of the guides together below the table top, and means for continuously supplying liquid to the spout so that it will overflow the lip and pass downwardly between the guides in the form of a thin film.

5. A liquid display device comprising a spout, a reservoir for storing the liquid, a supply pipe connecting the reservoir with the spout, a pump for forcing the liquid through the supply pipe, and a valved by-pass line connecting with the supply pipe for by-passing excessive quantities of the liquid being pumped back to the reservoir so that only a predetermined quantity of liquid will pass to the spout.

6. A liquid display device comprising a spout, a reservoir for the liquid being pumped, a supply pipe connecting the reservoir and the spout, means for pumping the liquid from the reservoir through the supply pipe, and means for regulating the quantity of liquid delivered to the spout, including an independent valved by-pass line connected with the supply pipe for by-passing regulated quantities of liquid from the supply pipe back to the reservoir.

7. A liquid display device comprising a spout, a reservoir for the liquid being pumped, a supply pipe connecting the reservoir with the spout, means for forcing the liquid continuously through the supply pipe, and a valved by-pass pipe, having one end thereof extending into the supply pipe, said end being beveled to form a projecting lip

on the upper side to insure the by-passing of some of the liquid passing through the supply pipe upon the opening of the valve in the by-pass line.

5. 8. A liquid display device comprising a spout, a reservoir for storing the liquid, a supply pipe connecting the reservoir with the spout, a pump for forcing the liquid through the supply pipe, a valve in the

supply pipe for regulating the quantity of liquid pumped therethrough, and a valved by-pass line connecting with the supply pipe for by-passing excessive liquid to the reservoir.

In witness whereof I have hereunto set my hand and seal this 17th day of November, 1926.

ARTHUR LEFEVRE, JR.
